UNITED STATES PATENT OFFICE.

GEORGE EDWARD WHITE, OF GWELO, SOUTH RHODESIA, SOUTH AFRICA.

WELL-PUMP.

1,138,432.

Specification of Letters Patent.

Patented May 4, 1915.

Application filed December 7, 1912. Serial No. 735,408.

To all whom it may concern:

Be it known that I, GEORGE EDWARD WHITE, a citizen of the United States of America, and a resident of Gwelo, South Rhodesia, South Africa, have invented a new and Improved Well-Pump, of which the following is a full, clear, and exact description.

The invention is an improvement in pumps and has for its object to provide an inexpensive, simple and balanced pump.

To carry out the above said object I employ a pump having a reciprocating plunger actuated by a tubular rod having a valve controlled opening.

The invention consists of the construction and combination of parts to be more fully described hereinafter and fully set forth in the claims.

Reference is to be had to the accompanying drawings forming a part of this specification, in which like characters indicate corresponding parts in all the views.

The drawings represent an elevated section of an embodiment of my invention.

Before proceeding to a more detailed description of my invention, it must be understood that while my pump is principally constructed for operation with a wind motor, the same may be used with a different motive power by a certain modification in parts without departing from the underlying spirit of the invention.

Referring to the drawing, 10 is a strainer positioned at the lower end of the suction pipe 11 extending from the suction casing 12, which is closed and flanged at the top. Another casing 13, flanged at both ends, is attached by means of bolts with its lower flanged end to the flanges of the casing 12. The casing 13 contains two cylinders 14, spaced from each other, open on both ends, and into which are fitted plungers 15. Engaging the casing 13 at both upper and lower flanges is the delivery casing 16 through which the liquid from the lower portion of the well is raised by means of the plungers to the desired place.

The top of the suction casing 12 is provided with valve controlled openings 17, lying preferably in the axes of the cylinders 14, and the valve 18, controlling the openings in each cylinder, is caged by means of a cage member 19 bolted to the top of the suction casing 12 and projecting into the cylinder 14. The plungers 15 reciprocating in

the cylinders 14 are, near their lower ends, provided with packing rings 20 and a valve-controlled orifice 21. A valve 22 is provided for each plunger, controlling the orifice 21, 60 and caged to prevent excessive displacement of the valve 22 during the flow of the liquid through the opening 21 of the plunger. The plungers are also provided with a passage 23 leading from the valve controlled 65 opening 21 to the lateral surface of the plunger; the cross section of the passage being such that at any particular place its cross-sectional area is not less than the cross section of the valve controlled opening 21, 70 and preferably substantially equal to same.

The upper portion of the plunger 15 is provided with a tubular rod 23' integrally formed with the plunger or in any other way rigidly connected to the same. The tubular 75 rods 23' are each provided with a valve controlled opening 24 near the top of the plunger 15. The opening 24 is controlled by a valve 25 mounted on a pivot 26 projecting through the lateral surface of the tubular 80 rod 23' near the opening 24 and lying in a plane normal to the axis of the opening. The projecting ends of the pivot 26 are rigidly attached to a yoke member 27, so that by moving the yoke 27 the valve 25 may be 85 displaced about its axis, which is the pivot 26. The delivery casing 16 is on its lateral surface provided with set screws 28 adapted to engage the yoke 27 controlling the valve 25 of the opening 24, that is, operating the 90 valves 25 at the upper and lower points of the length of the displacement of the plunger.

The operation of the pump is as follows: During the upward displacement of the 95 right-hand plunger the valve 25 of the tubular rod 23' is open and the liquid inclosed in the tubular rod communicates with the liquid inclosed in the delivery casing. The valve 22 in this plunger will seat itself on 100 the valve seat and close the opening 21, thereby creating a vacuum in the right cylinder 14 and the liquid from the well will, consequently, raise the valve 18 controlling the opening 17 into this cylinder, and the 105 same will be filled when the right-hand plunger reaches its uppermost point. During this upward motion of the right-hand plunger the liquid in the delivery casing and the tubular rod are continuously communicating. When the right-hand plunger reaches its uppermost position the yoke 27 comes in

2

contact with the set screw 28 and closes the valve opening 24 by means of the valve 25, thereby severing the communication between the tubular space in rod 23' and the delivery casing 16. During the same time, the left-hand plunger is going downward with its opening 24 of the tubular rod 23' closed. The liquid inclosed in the left-hand cylinder 14, due to the downward motion of the plunger, raises the valve 22 in the plunger and passes through the passage 23, entering the delivery casing 16. The valve 25 of the tubular rod 23' remains closed until about the lowermost position of the plunger, when it is opened by the lower set screw 28 engaging the yoke 27 and thereby displacing the valve 25 and establishing communication between this tubular space of the rod 23' and the delivery casing.

20 While the drawing discloses a special construction of a valve for the opening 24 in the tubular rod 23', any suitable valve may be used for the purpose. The compound construction of the pump as shown in drawing gives a continuous flow of liquid from the well and is better balanced.

Having thus described my invention, what I claim and desire to secure by Letters Patent is:

30 1. A well pump comprising a cylinder; a delivery casing above said cylinder, said cylinder having a valve-controlled inlet; a plunger in said cylinder having a valve-controlled outlet from said cylinder to said delivery casing; a tubular rod in said casing for reciprocating said plunger, having an opening and a valve to control said opening; and means on said delivery casing adapted to operate said valve in said rod at predetermined points, thereby establishing or severing the communication between said delivery casings and said tubular rod.

40 2. A well pump comprising, a casing, a

pair of cylinders each having a valve-controlled inlet in said casing; a delivery casing 45 above said casing for both of said cylinders; a plunger in each of said cylinders having a valve-controlled outlet from said cylinders to said delivery casing; a tubular rod for each of the said plungers in said delivery casing 50 and substantially parallel to it, each of said tubular rods having an opening and a valve to control said opening; and means on said delivery casing adapted to operate each of said valves in said tubular rod when said 55 rods reach substantially the end of their up and down stroke.

3. A well pump comprising, a cylinder having a valve-controlled inlet; a delivery casing for the cylinder and above same; a 60 plunger in said cylinder having a valve-controlled outlet from said cylinder to said delivery casing and a tubular rod associated with said plunger, said tubular rod having an opening near the top of said plunger establishing communication between said tubular rod and said delivery casing; a valve for said opening; a pivot secured to said valve and projecting through said tubular rod and a yoke rigidly secured to the projecting ends of said pivot by means of which 65 said valve could be operated, and thereby control the opening in said tubular rod; and means at predetermined points on the lateral surface of said delivery casing adapted to 70 engage said yoke during the reciprocation of said tubular rod, thereby controlling the communication between said tubular rod and said delivery casing.

In testimony whereof I have signed my 80 name to this specification in the presence of two subscribing witnesses.

GEORGE EDWARD WHITE.
